UNITED STATES PATENT OFFICE.

FRANK M. PIERCE, OF CHICAGO, ILLINOIS, ASSIGNOR TO PIERCE WRAPPING MACHINE COMPANY, OF CHICAGO, ILLINOIS, A CORPORATION OF ILLINOIS.

PAPER-CARRIER FOR WRAPPING-MACHINES.

1,221,089.

Specification of Letters Patent.

Patented Apr. 3, 1917.

Original application filed October 3, 1914, Serial No. 864,735. Divided and this application filed October 4, 1915. Serial No. 54,098.

To all whom it may concern:

Be it known that I, FRANK M. PIERCE, a citizen of the United States, and a resident of the city of Chicago, in the county of Cook and State of Illinois, have invented certain new and useful Improvements in Paper-Carriers for Wrapping-Machines; and I do hereby declare that the following is a full, clear, and exact description of the same, reference being had to the accompanying drawings, and to the numerals of reference marked thereon, which form a part of this specification.

This invention constitutes a divisional application of my co-pending application for "tire wrapping machines," filed October 3rd, 1914, Serial No. 864,735.

This invention relates to a carrying means for paper on the revolute type of shuttle used in high speed wrapping machines for annular or other articles required to be inserted through the eye of the shuttle to receive a wrapper applied thereon.

In this type of wrapping machine a reel of the wrapping material is generally mounted upon a suitable spindle on the shuttle from which the strip is unwound and at times when the machine is operating at high speed and is brought to a sudden stop after the completion of a wrapping operation the reel of wrapping material tends to continue rotation so that the overtravel causes an excess of paper to be unrolled therefrom.

This invention, however, relates to a mechanism adapted to receive a reel of wrapping material inserted thereon without requiring adjustment of the parts and acting as a friction brake for the reel to prevent overtravel thereof when the machine is suddenly brought to rest.

It is an object therefore of this invention to construct a reel carrying device embracing resilient friction means for contact with the inner layer of the paper of the reel to prevent overtravel of the reel of paper as the reel is rotated to unwind the paper therefrom.

It is also an object of this invention to construct a paper carrying device for a revolving shuttle on high speed wrapping machines embracing a spindle having a plurality of resilient members associated therewith to engage the reel of paper to hold

the same in position thereon and to prevent overtravel of the reel as the same is rotated to unwind the paper therefrom.

It is furthermore an important object of this invention to construct a paper carrying device comprising a disk having a spindle projecting centrally therethrough and provided with a sleeve slotted to receive resilient means engaged therewith for contact with a reel of paper inserted on the device to act as a friction brake to prevent spinning of the reel as the same is rotated to unroll the paper therefrom.

It is finally an object of this invention to construct a paper carrying device for a reel of paper provided with resilient frictionally acting means to prevent over-rotation of the reel as the paper is drawn therefrom.

The invention (in a preferred form) is illustrated in the drawings and hereinafter more fully described.

On the drawings:

Figure 1 is a front elevation of a shuttle equipped with a device embodying the principles of my invention showing a reel of paper mounted thereon.

Fig. 2 is a side view of the mechanisms shown in Fig. 1.

Fig. 3 is a section taken on line 3-3 of Fig. 1, with the paper reel omitted.

Fig. 4 is a front face view of the device with the reel of paper omitted.

Fig. 5 is a detail plan view of the slotted sleeve forming a part of the paper carrying device.

As shown in the drawings:

The shuttle consists of a main section 1, and a supplementary section 2, pivotally connected therewith adapted to be locked to said main section by a locking device 3, to afford a closed ring. Mounted on the front surface of the main section 1, through an aperture provided for the purpose, is a bolt 4, affording a spindle being secured on the opposite surface of the main section 1, of the shuttle by means of a nut 5, as clearly shown in Fig. 3. Integrally formed upon said spindle 4, is a collar 6, which bears against the front surface of said shuttle section 1, and affords a means of attachment on said spindle of a reel supporting disk 7. Inserted over the outer end of said spindle 4, is a sleeve 8, which on diametrically opposite sides is cored out to afford slots 9.

For the purpose of retaining said sleeve in place upon the spindle, a cap 10, is provided mounted on the end of the spindle and held secured thereon by means of a bolt 11, threaded into the spindle. Mounted in the slots 9, of said sleeve are a pair of leaf springs or resilient members 12, which are compressed almost entirely into the slots 9, when a reel of paper 13, is inserted thereover. Said resilient members bear frictionally against the inner layer of paper of the reel in a manner to permit rotation of the reel as the strip of paper is drawn therefrom and yet acting to prevent overtravel or spinning of the reel when the machine is suddenly stopped. The strip drawn from the reel of paper 13, is first led through a tension device 14, then through a folder plate 15, finally around a creasing roller 16, and thence to the article being wrapped.

I am aware that other means falling well within the scope of my invention may be used for obtaining the results achieved by my device, but I do not purpose limiting the patent granted otherwise than necessitated by the prior art.

I claim as my invention:

1. In a device of the class described the combination with a shuttle of a spindle mounted thereon, a collar integrally formed on said spindle, a supporting disk secured thereto, a sleeve on said spindle resting on said disk and having slots therein, resilient means engaging in said slots of said sleeve, and means for retaining said sleeve upon

said spindle and adapted to receive a reel of paper inserted thereover to compress said resilient means whereby the same acts as a brake for the reel of paper to prevent spinning thereof on the device. .

40

2. In a device of the class described a spindle, a collar integral therewith, a disk secured thereon, a sleeve on said spindle resting on said disk, a cap retaining said sleeve on said spindle, and resilient means engaged with said spindle adapted to contact the inner layer of a reel of paper mounted on said device to prevent spinning thereof on the device and yet permitting rotation of said reel on the device.

45

3. In a paper carrying device of the class described the combination of a shuttle and a spindle rigidly secured therein, a disk rigid on said spindle, a sleeve resting thereon having slots therein, a cap mounted on the outer end of said spindle and sleeve, a bolt projecting through said cap and threaded into said spindle to hold the sleeve in position, and a pair of resilient members disposed in said slots in opposite sides of said spindle acting to contact a reel of paper inserted on the device to prevent spinning of the reel thereon.

In testimony whereof I have hereunto subscribed by name in the presence of two subscribing witnesses.

FRANK M. PIERCE.
